UNITED STATES PATENT OFFICE.

CHARLES C. WILLIS, OF FRAMINGHAM CENTER, MASSACHUSETTS, ASSIGNOR TO DENNISON MANUFACTURING COMPANY, OF FRAMINGHAM, MASSACHUSETTS, A CORPORATION OF MASSACHUSETTS.

CREPE-PAPER FESTOON.

Application filed March 5, 1927. Serial No. 173,098.

This invention relates to paper articles and more particularly to paper festoons adapted to be used in various well understood manners for purposes of decoration.

5 A paper festoon of this character ordinarily consists of two superposed strips or ribbons of crepe paper having marginal fringes, and in use the festoon is customarily twisted to give a spiral effect and suspended in 10 loops about the space to be decorated.

The principal object of this invention is to provide simple yet efficient means for easily and economically reinforcing the paper festoon against longitudinal strain, and 15 for the attainment of this purpose, a string is longitudinally disposed intermediate the superposed strips of crepe paper and is secured therebetween by pasting the two strips together over the central longitudinal string.

20 I am aware that paper festoons have been made by stitching two strips of crepe paper together along their longitudinal median line, but the manufacture of such strips requires the provision of expensive machinery

25 which is adapted to furnish a festoon of limited length, the stitches are apt to unravel in use, and the resulting perforations in the crepe paper appreciably weaken the paper. A festoon constructed in accordance

30 with the present invention is stronger than the stitched festoon and the expense of manufacture is considerably lessened owing to the speed with which an article of unlimited length may be prepared and the

35 saving in cost resulting from the use of a single, straight string or thread instead of the double, looped thread in the stitched festoon.

A crepe paper festoon embodying the invention is illustrated in the accompanying drawing, in which:

Fig. 1 shows the improved festoon twisted in spiral form for use;

Fig. 2 is a plan view of the festoon with 45 a portion of the top paper strip broken away to show the disposition of the string; and

Fig. 3 is a section on the line 3-3 of Fig. 2.

The article preferably consists of two 50 similar superposed strips 4 and 5 of narrow

crepe paper ribbon, and a string, thread or cord 6 longitudinally disposed between the two strips substantially along the median line thereof. The strips are secured to each other and to the string by the application of any suitable adhesive, such as paste, mucilage or glue, along said median line, preferably leaving a substantial portion of the margins unpasted. These margins preferably have transverse cuts or slits, as at 7, 55 providing the usual fringe of the finished festoon, and in such case it will be seen that the longitudinal stress of the completed festoon is borne by the relatively narrow strip of material along the median line 60 of the ribbon. The reinforcing means provided by this invention is peculiarly adapted to strengthen a narrow strip of this character.

The festoon may be made by hand or by appropriate machinery. In case machinery is employed, it has been found that several festoons may be pasted and fringed simultaneously with great rapidity, the speed of output being limited only by the speed of the 75 fringe cutters.

An article so constructed will effectively resist the inherent tendency of the crepe paper to stretch longitudinally under tension, is easy to manipulate and durable in 80 use, and provides a festoon which is pleasing in appearance, especially when the crepe paper strips are tinted in harmonizing or contrasting colors.

It will be apparent that the festoon may 85 comprise three or more strips of crepe paper and additional strings pasted as aforesaid between each juxtaposed strip, and that the intermediate layers may be colored differently than the outer layers in order to enhance 90 the attractiveness of the article.

I claim:

1. A paper festoon consisting of superposed strips of crepe paper and an intermediate longitudinal string adhesively secured to the adjacent strips. 95

2. A paper festoon consisting of two superposed strips of crepe paper and a longitudinal string disposed between the said strips substantially along the median line 100

of the festoon, said strips being pasted to the string and to each other along said median line.

3. A paper festoon consisting of two superposed strips of crepe paper and a longitudinal string disposed between the said strips substantially along the median line of the festoon, each of said strips having

transverse slits extending inwardly from each of its margins and being adhesively secured to said string substantially along its median line.

Signed by me at Framingham, Massachusetts, this twenty-fifth day of February, 1927.

CHARLES C. WILLIS.
